UNITED STATES PATENT OFFICE

JAMES FLOCKHART, OF SAN FRANCISCO, CALIFORNIA, ASSIGNOR TO THE FLOCKHART COMPANY, OF SAN FRANCISCO, CALIFORNIA, A CORPORATION OF CALIFORNIA

FOUNTAIN BRUSH

Application filed September 30, 1929. Serial No. 396,082.

This invention relates to improvements in fountain brushes for applying paint or heavy ink to surfaces. It relates more particularly to brushes or spreaders of the 5 squeegee type, used in stencil work, and the like.

Among the objects of the invention is to provide a fountain brush in which the feed of the paint is adjustably controlled at all 10 times.

Another object is to provide separate compartments in equal or different proportions for several kinds of paint.

Another object is to provide a brush of 15 this type of simple design and strong construction, and one which may be readily taken apart for cleaning.

Other objects and advantages will appear 20 as the description progresses.

In this specification and the accompanying drawings, the invention is disclosed in its preferred form but it is to be understood that it is not limited to this form, because it may be embodied in other forms. It is also to 25 be understood that in and by the claims following the description, it is desired to cover this invention in whatsoever form it may be embodied.

In the accompanying one sheet of drawing:

Figure 1 is a front elevation of the brush.

Figure 2 is a section taken on the line II-II of Figure 1.

Figure 3 is a rear elevation of the brush.

Figure 4 is a plan of the brush having parts broken away for purposes of illustration.

The main body 1, of the brush, is preferably cast in one piece of light metal. It has the ends 2 and 3 joined by the upper front side 4 and the curved lower front side 5, which projects to form the front wall of the paint reservoir 6, open at the top 7 to receive the paint.

The back wall of the reservoir consists of a plate 8 having a rubber strip 9 clamped on its lower edge by the plates 10 and 11, by means of the screws 12. The rubber strip projects below the point 13 of the side 5.

The plate 8 is pivoted on the ends 2 and 3

by means of the lugs 14 and 15 fixed to the plate, and the rod 16 which extends through the lugs and the ends. A spring 17 acts to hold the lower end of the plate against the side 5. The lower edge of the plate 11 engages the inside edge 18 of the side 5 and the rubber strip presses against the point 13 of the side 5.

The top portion of the plate 8 has the projection 19 and serves as a handle for the use 30 of the operator when pressing in the top of the plate 8 to open the lower end to allow paint to flow out.

Screws 20 and 21 in the plate 8, engaging the back 4 are provided to adjust the amount 35 of the opening and thereby the amount of paint fed out. The partitions 22 and 23 are laterally slidable on the rod 24. The rod 24 engages the enlarged holes 25 in the sides 2, 3 to allow for the partitions adjusting themselves to the inside of the reservoir and to the plate 8 when the plate 8 swings open. Only slight adjustment is needed as the paint is heavy and does not require very 40 tight joints between the partitions and the 75 walls.

In the operation of the brush if one kind of paint is to be used the partitions are moved along the rod to the ends and the reservoir is filled. But if two or more kinds of 45 paint are used, the partitions are moved along the rod to divide the reservoir into two or more compartments, each to be filled with the required color of paint.

The brush is moved over the surface to be 50 painted, in the direction indicated by the arrow, with the plate 8 pressed in at the top until the screws 20 and 21 come in contact with the front member 4 to feed the paint to the surface and distribute it by the squeegee 9. 90

The action of this brush is in reality automatic; as the brush is moved in the direction of the arrow with the rubber strip in contact, the friction tends to swing the lower end of the plate 8 back and allow the paint to feed. 95

Near the end of the stroke of the brush over the work the plate is released and the spring throws it to bring the lower edge of the plate 11 against the edge 18 and the rubber strip against the edge 13 of the reservoir 100

to cut off the flow of paint. To get the right amount of paint for each stroke, the screws 20 and 21 are adjusted so that the opening of the plate is regulated to deliver the amount required.

5 Having thus described my invention, what is claimed and desired to secure by Letters Patent is:

- 10 1. A fountain brush of the class described, comprising a flat body member having an open paint reservoir extending across its lower end, a plate extending across the body member from side to side, and top to bottom, and forming one wall of the reservoir, a transverse pivot member intermediate the top and bottom, a spring acting to hold the plate in contact with the bottom of the reservoir, and a rubber spreader secured to the bottom of said plate.
- 15 2. A fountain brush of the class described, comprising an open paint reservoir, a handle portion extending upward from said reservoir, a pivoted plate in the handle portion and extending downwardly to form the rear wall of the reservoir, adjustably spaced partitions in said reservoir, a resilient spreader secured to the bottom edge of said pivoted plate, and means to tilt said plate to allow paint to feed from the reservoir to be spread by said spreader.
- 20 3. A fountain brush of the class described, comprising a plate having a resilient strip secured to the bottom edge thereof, a body member having an open paint reservoir projecting therefrom, said plate being pivoted to and forming the back wall of said reservoir, means to hold said plate in the closed position, means to move said plate to allow a predetermined amount of paint to flow from said reservoir as the brush is moved over the surface to be painted.
- 25 4. A fountain brush of the class described, comprising a body member, an open paint reservoir, a movable plate pivoted to said body member and forming the back wall of said reservoir, a resilient strip secured to the lower edge of said plate and in substantially the same plane as said plate, means to move said plate to permit the flow of paint, and 40 adjustable means to limit the throw of said plate.
- 30 5. A fountain brush of the class described, comprising a body member, a reservoir for holding paint in said body, a pivoted plate forming the back wall of said reservoir, a weight forming part of the top of said plate to hold said plate in contact with the bottom of said reservoir, a spring to augment the effect of said weight, and a resilient spreader 45 secured to the lower edge of said plate.

In testimony whereof I have hereunto set my hand this 20th day of September, A. D. 1929.

JAMES FLOCKHART.
